UNITED STATES PATENT OFFICE.

JOSE M. ALMEDIA, OF ROCK SPRINGS, WYOMING.

ROTARY PRINTING MACHINE.

Application filed December 22, 1921. Serial No. 524,242.

To all whom it may concern:

Be it known that I, JOSE M. ALMEDIA, a citizen of the United States, residing at Rock Springs, in the county of Sweetwater and State of Wyoming, have invented certain new and useful Improvements in a Rotary Printing Machine; and I do hereby declare the following to be a full, clear, and exact description of the invention, such as will enable others skilled in the art to which it appertains to make and use the same.

This invention relates to a rotary printing machine particularly of the type employing manually operable rotary cylinders.

An important object is to provide a means whereby printed sheets may be delivered from a printing machine with the ink thereon substantially dry.

A second object is to effect said object by the use of an absorbent or blotting means engageable by the printed faces of the sheets during travel through the machine.

A third object is to provide means whereby the paper is resiliently urged into effective contact with the printing cylinder and also with the blotting means and means whereby such means may be moved out of operative relation with the cylinders to facilitate preparation thereof.

A fourth object is to provide an improved shaft means for driving and detachably mounting the printing cylinder.

A fifth object is to provide an inking means which may be carried by the printing cylinder, such a means as may be movable within the cylinder for effective cooperation with the operating surface of the cylinder, one having an operating means normally folded into the cylinder and one having the inking mechanism movably mounted in the shaft.

A sixth object is to provide an improved paper table and receiving basket foldable into compact relation with the remainder of the machine and with one of said parts having means to support it and which is operable to secure the table in folded relation.

Additional objects and advantages will become apparent from a consideration of the description following taken in connection with accompanying drawings illus-

trating one practical embodiment is illustrated.

In said drawings:—

55

Figure 1 is a plan view of the improved machine;

Figure 2 is a side elevation thereof with the folded position of the paper table extension and the receiving basket adjusted in dotted lines;

Figure 3 is a front elevation;

Figure 4 is a longitudinal sectional view on the line 4—4 of Figure 1;

Figure 5 is a transverse sectional view 65 on the line 5—5 of Figure 1 taken through the printing cylinder;

Figure 6 is a cross sectional view on the line 6—6 of Figure 1 taken through the blotting cylinder;

70

Figure 7 is a cross section on the line 7—7 of Figure 2 taken through the position varying for the pressure rolls of the printing and blotting cylinders;

Figure 8 is a transverse sectional view 75 on the line 8—8 of Figure 1 taken through the paper gages and cable mounting them;

Figure 9 is a side elevation of the inking device looking toward the shaft-engaging latch, with the handle raised and the lower 80 position adjusted in dotted lines;

Figure 10 is a side elevation of said inking device taken at a right angle to Figure 9;

Figure 11 is a plan view of said inking 85 device with the handle in lowered position;

Figure 12 is a vertical sectional view on the line 12—12 of Figure 10;

Figure 13 is a detail perspective view 90 illustrating the blotting cylinder;

Figure 14 is a section on the line 14—14 of Figure 7, and

Figure 15 is a detail perspective view of a fragmentary portion of the absorbing sheet.

95

Like reference characters designate like or similar parts throughout the different views.

In reducing the invention to practice, a base may be provided at 10 having depending feet or rests 11, preferably of a resilient nature, and adapted to directly engage a support, such as a table top. Rising from the base 10 are mounts or standard

100

- member 12 which have bearings at 13 in which a shaft 14 is journaled which supports and is adapted to impart motion to a printing cylinder 15. Cooperating with the printing cylinder 15 is a blotting cylinder 16 movable with a shaft 17 journalized in bearings 18 of said mounts 12. It will be noted that the mounts 12 are skeleton castings, that the bearings 13 and 18 are integral with the mounts and that they are provided with strengthening and reinforcing flanges 19. Bolts 29 may pass through the lowermost flanges 19 and the base 10 in order to secure the mounts in place.
- 15 The printing cylinder may be of any preferred type and as shown has skeleton end disks 22 to the periphery of which is suitably fastened as at 23, a perforated cylindrical diaphragm or wall 24. As is usual in a printing machine of this type, an absorbent inking mat 25 surrounds said diaphragm and a printing form such as a stencil or perforated flexible sheet 26 is disposed thereover. Fastened to and spanning the disks 22 is an attaching bar 27 provided with struck out prongs 28 on which said mat and stencil may be hooked adjacent one end. Said mat and stencil adjacent the opposite ends are turned into the cylinder and engaged by a clamping bar 29 movable from pivots 30 on disks 22, and which binds said ends tightly but removably in place.
- 20 Shaft 14 is round and removable from the cylinder and the bearings 13. It is provided however with squared portions 31 which slidably but removably fit into squared openings 32 in hubs 33 of disks 22. Beyond one of the bearings 22, said shaft is provided with a crank 34 from which a horizontal handle 35 extends. A removable cotter pin or other means may pass through an opening in the shaft 14 to normally prevent removal or displacement thereof.
- 25 Blotting cylinders may consist of a cylindrical drum 37 fastened on end disks 36 which have hubs 39. Shaft 17, except for the portion journaled in bearings 18, is preferably square as at 40, and such squared portion passes removably through square openings 41 in said hubs 39. Said shaft 17 is also preferably removably mounted in the bearings 18 and openings 41 and it is normally held in place against displacement by means of a cotter pin 42 passing through an opening thereof.
- 30 On drum 37, a blotting and ink absorbing means, such as a blotter or ink absorbing sheet 43 is provided. This sheet is of the usual flexible nature so that it may conform to the shape of the drum 37 and inasmuch as it should be renewed from time to time, it is removably fastened. The fastening may be accomplished in any suitable manner. For instance, at one end of the sheet 43 reinforcing tabs 44 are provided having open- ings therethrough adapted to fit over lugs 45 projecting from the drum. The opposed end of such sheet is also provided with reinforcing tabs 46 having openings therethrough into which securing latches 47 extend. Latches 47 are depressible so that they may engage and disengage the tabs 46. Said latches may slide through the drum 37 and also through the brackets 38 and have an expansive spring 49 to surround the same intermediate the bracket and drum, and suitably fastened to normally urge the latches into fastening position. A manipulating arm or finger 50 projects from each latch 47 and beyond the ends of drum 37 and such arms rest on the springs 49 so that depression of the fingers 50 will tension the springs 49 for return movement to engagement with tabs 46.
- 35 A suitable means is provided whereby the motion of the shaft 14 for printing cylinder 15 may be imparted to the blotting cylinder. To this end, I have shown a sprocket wheel 51 rigid on shaft 13 and a sprocket wheel 52 rigid on shaft 17 and with a sprocket chain 53 traversing them.
- 40 An one end of the machine, adjacent the printing cylinder 15, a suitable board or table is provided at 54 which may be mounted in any suitable manner, as by screws 55 passing through the mounts 12 and into the same. Such table 54 may have a longitudinal extension or leaf 56 adapted to be folded into compact relation against the machine and to this end preferably by a hinge as at 57 to said table 54. This leaf is also preferably provided with grooves at 58 to accommodate the fingers arranging the pile of paper or sheets thereon preparatory to printing.
- 45 In order to properly guide the paper sheets to the cylinder 15, a plurality of gage members are provided. These gage members are designated 59 and have vertical walls 60 between which the paper sheets pass. They also have lateral flanges 61 through which bolts 62 pass and above which they preferably receive their nuts 63. Said bolts pass through the table 54 and are movable laterally in elongated slots 64 so that the gages may be set at different positions according to the width of the paper and the printing form. The heads or bolts 65 are preferably square and the slots 64 are enlarged at 66 to correspond to the shape of the heads 65 in order to receive said heads and prevent turning of the bolts 62.
- 50 Disposed below the blotting cylinder 16 is a platen roller 67. A similar platen roller 68 is disposed below the printing cylinder 16. These rollers 67 and 68 are similar and each is provided preferably with a rubber covering or surface at 69 and 70, respectively. Said rollers 67 and 68 have trunnions 71 journaled in bearings 72 prefer- 120
- 55 125
- 60 130

ably integral with or forming parts of levers 73, fulcrumed as at 74 on brackets 75 secured to the base. It is to be noted that the forward end of the table 54 rests on 5 the adjacent brackets 75 to increase its support and that the adjacent upper surface of said table 54 is curved toward the roller 67 to facilitate the feed of the paper sheet intermediate said roller 67 and the cylinder 10. Springs 76, as of the coil expansive type, urged the levers 73 upwardly so rollers 67 and 68 coact with an cooperate with their respective cylinders. These springs are interposed between the base and the 15 levers 73, preferably surrounding studs or pins 77 rising from the base and extending through elongated slots 78 in said levers 73. Two of said levers 73, overlap the remainder of said levers as at 79. As it is desirable at times to move said rollers 67 and 20 68 out of engagement with their respective cylinders, for instance when inking the pads or mats 25 or when attaching a new blotter 43, a suitable means to depress them 25 is provided. To this end, a shaft 80 is journaled in the mount 12 and is provided with eccentrics or cams 81 operatively engaged with the adjacent levers 73 and which shafts 80 have an operating crank 82 provided 30 with a handle 83. It will be obvious that upon operation of the handle 83, shaft 80 will be turned which through the medium of cams 81, and the fact that the levers 73 engage thereby overlap the other levers at 35 79, said cam will depress all of the levers 73 and thus simultaneously move the rollers 67 and 68 away from their respective cylinders.

Intermediate the rollers 67 and 68, a substantially horizontally disposed plate 84 is provided to guide the printed sheets from the cylinder 15 and the roller 67 to the roller 68 and blotting cylinder 16. This plate 84 has standards 85 depending therefrom and secured as at 86 to the base 10. Said shaft 80 utilizes said standards 85 as well as the mounts, as bearings. Also rising from the plate 84 are side guard flanges 87 to prevent lateral displacement of the 50 printed sheets as they pass thereover.

At the rear of the machine, a discharge plate 88 is provided for the printed sheets and arranged at a point below cylinders 16 adjacent to rollers 68. Plate 88 has depending standards 89 secured at 90 to the base 10. It also has upstanding guide flanges at 91. The discharge end of said plate 88 is deflected downwardly at 92.

A basket or receptacle 93 is disposed at 60 the rear end of the machine so as to receive the printed sheet from the plate 88. This basket may be of any suitable construction and is preferably reticulate as shown. The front end of said basket 93 is preferably 65 hinged by means of pilots 94 to the base

end so as to be capable of folding movement against the machine as shown in dotted lines in Figure 2. The basket is suspended in a horizontal position by means of hook rods 95 pivoted to the basket at 96 and having their forward end or hooks 97 engageable in apertures or eyelets 98 provided on the mount 12. To the undersurface of the leaf 56, eyelets 99 are provided and they project laterally beyond the side of the leaf so that when said leaf and the basket 93 are in the folded position suggested by dotted lines in Figure 2, the hooks 97 may be engaged in said eyelets 99 to hold the parts in compact relation.

Referring now to the inking device 25, it is carried by and disposed with the cylinder 15 and consists of a suitably shaped ink container or receptacle 100 whose reservoir is spanned by a transverse tube 101 through which shaft 14 passes and on which shaft it is capable of rotation. Said receptacle 100 carries a brush or applicator 102 which has applying bristles or other means 103 disposed in contact with the interior of the diaphragm 24. Said bristles extend from a head 104, which may be disposed intermediate flanges 105 on the receptacle 100 and be secured in place by screws 106 passing through said flanges 105 and into head 104. Ink may flow from the receptacle 100 through an opening 107 in its bottom and which communicates with an opening 108 in said head 104 so that the ink may flow to the applying means 103. Associated with the opening 107 is a valve 109 of the needle type, which is operable to vary the extent of the opening and which may be carried by a rod 110 having a screw portion 111 thereon threaded into an opening 112 in the top of the receptacle 100 and also having an operating handle or portion at 113. Receptacle 100 has a filling opening 114 normally closed by a closure cap 115 removably screwed in place. A stud 116 rises from the top of said receptacle 100 and has a vent opening 117 therethrough which may be opened or closed according to the position of a valve in the form of a lever 118 pivoted at 119 to said stud 116. A loop or arched bar 120 is provided at the top of receptacle 100 and a suitable handle 121 is pivoted thereto as at 122. Movement of said handle 121 to an operative position is limited by a stop or abutment 123 integral with the loop 120. Normally said handle 121 is folded toward the receptacle 100 and disposed within the cylinder 15.

While the receptacle 100 is capable of rotation on the shaft 14, yet it is normally held against movement relatively to the shaft 14 and cylinder 15. To this end, one extremity of tube 101 as at 124 has a square opening which is adapted to slidingly en-

gage over one of the squared portions 31 to thus couple the receptacle to shaft 14 against independent turning. In order to prevent detachment of said portion 124 from the adjacent squared portion, accidentally, a suitable means is provided. To this end, said shaft 14 may have a continuous groove surrounding the same as at 125 to be entered by a latch 126. This latch is 10 slidably mounted on receptacle 100 as through spaced barrels 127. Surrounding the latch 126 intermediate barrels 127 is an expansive coil spring 128 engageable with a projection 129 on the latch so as 15 to normally urge the latch through the said groove 125. A laterally extending lug 130 is provided on latch 126 to facilitate manipulation thereof to release the latch from the groove 125.

20 In practice, as stated, the inking device is disposed compactly within the cylinder 15 capable of movement independently thereof. Should it be necessary to ink the sheet 26, the handle 21 is moved to an operative position externally of the cylinder and the latch 126 is released from the groove 125 and the receptacle 100 is slid longitudinally of shaft 14 so as to disengage the squared portion of the tube at 124 from the adjacent squared portion of the shaft. It will be thus seen that in this condition, the receptacle 100 as well as the brush or applicator 102 is capable of sliding and rotatable movement on the shaft 14 relatively to the cylinder 15 and independently thereof. In such an instance, valve 109 being properly adjusted, one hand of the operator may grasp the handle 21 and the other hand of the operator may grasp the handle 121. 25 Such handles may be moved relatively in order to move the brush 102 over the entire inner surface of the diaphragm 24, so that the ink will flow through the perforations of said diaphragm and be absorbed by the ink mat 25. When the mat 25 has been sufficiently inked, valve 109 is closed and the receptacle 100 is moved longitudinally of the shaft 14 so that its squared portion 124 will engage the adjacent squared portion of said shaft 14 and the latch 126 will spring into the groove 125. The handle 121 may then be lowered. Thus the inking device will be held against movement independently of the cylinder and in 30 contact disposition within the same.

When the machine is in transit or out of use temporarily the parts are in the position shown in dotted lines in Figure 2. In order to use the machine, hooks 97 are disengaged from the eyelets 99 and thereupon the leaf 56 is secured with a level to the table 54 and the basket 93 is lowered and hooks 97 engage in eyelets 99 to support it in a substantially horizontal and receiving 35 position. The sheets of paper or other material to be printed are arranged upon the table leaf 56. With the gages 59 set relatively to the width of the paper, and with its stencil and ink mats properly arranged on the cylinder 15, such cylinder is turned in the direction of the arrows but the sheets are fed manually intermediate the gages 59 so that they will pass intermediate the cylinders 15 and the platen roller 67, in order to receive the printed impressions. The movement imparted to the sheets slides them on plate 84 and intermediate the rollers 68 and blotting means 43, so that the latter will absorb surplus moisture from each and will discharge the sheet 40 with such ink practically dry as a result, over the discharge plate 88 and into the basket 93, from which the same can be removed at will. It is clear that the stencil, inking mat and blotter may be removed or replaced at will and that during such operation, or whenever otherwise desired, the handle 83 may be turned so as to rock shaft 80 and cause cams 81 to depress the levers 73 and accordingly lower the platen rollers 67 and 68 and maintain them in a lowered position out of contact with the cylinders 15 and 16 until the machine is in condition for further use and they have been restored to normal position through turning of said handle 83 in the reverse direction.

As merely one embodiment of the invention has been illustrated and described, it is to be understood that it is capable of variation within the spirit and scope of the appended claims.

What is claimed is:—

1. A printing machine having printing mechanism, means operable to dry the ink from a printed sheet consisting of a drum, a blotting sheet to surround and fastened adjacent one end to the drum, and latch means on the drum engageable with the sheet adjacent the other end of the sheet.
2. A printing mechanism having a cylinder engageable with the sheet, a platen roller also engageable with the sheet, a lever on which said platen roller is mounted, means to urge movement of said lever toward the cylinder, means operable counter to said means to depress said lever, consisting of a turnable shaft, and a cam on said shaft directly engageable with said lever.
3. A printing machine having a plurality of cylinders engageable with the sheet, a platen roller cooperating with each cylinder, and means to simultaneously vary the position of said platen rollers.
4. A printing machine having a plurality of cylinders engageable with the sheet, a platen roller associated with each cylinder, and means to simultaneously depress all of said platen rollers away from said cylinders.
5. A printing machine having a plurality of cylinders engageable with the sheet, a

- platen roller associated with each cylinder, means to simultaneously depress all of said platen rollers away from said cylinders, comprising levers, springs to urge movement of the levers toward the cylinder, and positioning studs for said springs passing through slots and said levers.
6. A printing machine having a plurality of cylinders engageable with the sheet, a 10 platen roller for each cylinder, a lever mounting each platen roller, one of the levers overlapping the other lever, and means operable to depress the overlapping lever so as to simultaneously depress said 15 platen rollers.
7. A printing machine having an operative part thereof foldably mounted, means to support said part in an operative position, means to cooperate with said means to 20 also maintain said part in a folded position, consisting of a foldable part at the opposite end of the machine, and the last mentioned part having means engageable with said first mentioned means.
- 25 8. A printing machine having a printing member, an inking device therefor disposed therein and removable independently thereof, said device having a handle normally foldable within the member and capable of projection exteriorly of the member.
9. A printing machine having a printing member, a shaft mounting said member for rotation, an inking means journaled on said 30 shaft for movement relatively to said member during an inking operation, and means to secure said inking means to said shaft against movement independently thereof.
10. A printing machine having a printing member, a shaft mounting said member for rotation, an inking means journaled on said shaft for movement relatively to said member during an inking operation, means to secure said inking means to said shaft 35 against movement independently thereof, consisting of a substantially squared portion, means on the inking means substan-
- tially snugly receiving said portion, and latch means on the inking means cooperating with said shaft to prevent sliding of the 50 inking means relatively to the shaft.
11. A printing machine having a printing member, a shaft mounting said member to impart printing movement thereto, an inking means movable axially and longitudinally of said shaft to ink said member, means to prevent rotation of the inking means independently of the shaft, and means to prevent sliding movement of said inking means independently of the shaft. 55
12. A printing machine having a printing member, a shaft mounting said member means to impart printing movement thereto, and inking means movable axially and longitudinally of said shaft to ink said 60 member, means to prevent rotation of the inking means independently of the shaft, means to prevent sliding movement of said inking means independently of the shaft, consisting of a latch, and said shaft having 65 a continuous groove entered by said latch.
13. A printing machine having a printing cylinder, a shaft for said cylinder, an inking device within the cylinder consisting of a receptacle, a tube spanning the receptacle and journaled on said shaft, a handle for said receptacle to project beyond the cylinder and foldable within the cylinder, an applicator carried by said receptacle to receive ink therefrom, said applicator engageable against the interior of said cylinder said applicator having a squared portion, said tube having a squared portion slidably engaging the first mentioned squared portion, said shaft having a continuous groove, 75 and said receptacle having a latch to enter 80 said groove.

In testimony whereof I affix my signature in presence of two witnesses.

JOSE M. ALMEDIA.
